(57) **CLAIM**

The ornamental design for a medical device with display, substantially as shown and described.

DESCRIPTION

FIG. 1 is perspective view of a medical device with a display.

FIG. 2 is a front view of the medical device of FIG. 1.

FIG. 3 is a rear view of the medical device of FIG. 1.

FIG. 4 is a left-hand-side view of the medical device of FIG. 1.

FIG. 5 is a right-hand-side view of the medical device of FIG. 1.

FIG. 6 is a top view of the medical device of FIG. 1.

FIG. 7 is a bottom view of the medical device of FIG. 1; and, FIG. 8 is a sectional bottom view of FIG. 2 viewed along line 8-8.

The broken lines depict portions of the medical device with display that form no part of the claim.

In addition, the medical device with display may be of any color, shade, or combination of color and shades.

Also, the references to “perspective,” “front,” “back,” “side,” and “top” views in the Figure and Descriptions are not necessarily meant to require any specific orientation of the article as viewed. A medical device according to the claimed design may be used in any orientation.
